RADIATOR SUPPORT

Filed Sept. 28, 1925

UNITED STATES PATENT OFFICE

AUGUST KEHM, OF CHICAGO, ILLINOIS

RADIATOR SUPPORT

Application filed September 28, 1925. Serial No. 58,976.

This invention relates to the art of heating, and has for its principal objects to simplify the supports for the radiators; to permit the workmen to attach the supports 5 to the wall and to the radiators without assuming an awkward or uncomfortable position; to permit the supports to be attached to the wall by a single bolt; and to eliminate the necessity for attaching the support to the 10 wall at an exact distance apart.

Further objects and advantages of the invention will become apparent as the disclosure proceeds and the description is read in connection with the accompanying drawing, in which:

Fig. 1 is a partial sectional view illustrating a radiator support according to the present invention;

Fig. 2 is a side elevation of the combination shown in Fig. 1;

Fig. 3 is a fragmentary transverse section illustrating the preferred manner of attaching the support to a loop radiator;

Fig. 4 is a similar view showing the preferred manner of attaching the support to a wall radiator; and

Fig. 5 is a perspective view of the radiator support, with the radiator removed.

Referring to Fig. 1, 10 indicates a wall, 30 column or the like to which a radiator is to be attached, and by which the weight of the radiator is finally supported. 11 indicates a loop radiator carried by a leg 12, attached thereto above the center of gravity, and resting upon a stirrup 13 secured to the wall 10. 35 Preferably the leg is slightly curved, as best shown in Fig. 1, and, in the case of a loop radiator, is provided at its upper end with a yoke 14 (Fig. 3), having notches or seats 40 15 to receive the edges of the adjacent loops 16 of the radiator.

The yoke is perforated at 17, adjacent the middle, to receive a clamping bolt 18, which also passes through a clip 19, having arms 20 45 shaped to grip the opposite faces of adjacent loops 16. The head 21 of the bolt has a kerf 22, to receive a screw driver inserted between adjacent loops when the leg is being attached to the radiator.

50 The stirrup 13 is carried by a bracket 23,

and in order to permit the radiator to be readily set at the desired height, the stirrup is adjustably mounted on the bracket. This is accomplished by providing the two with complementary serrated sections and clamping them together by a bolt 24. The outer face of the bracket is provided with a pocket, surrounded by a rim or flange 25. The bottom of this pocket has two rows of serrations 26, separated by a slot 27, which communicates with a pocket 28 at the back side of the bracket. The stirrup is equipped with a slide 29, fitting the pocket on the outside of the bracket, having complementary serrations 30 on its inner face and perforated 60 to receive the stove bolt 24.

Since the leg 12 is attached to the radiator above the center of gravity, it will tend to swing clockwise in Fig. 1, and it is supported in a substantially upright position by an 70 abutment 31, against which it strikes at a point below the center of gravity. Preferably this abutment is formed by bending the lower end of the strap 32 which is secured to the wall.

75 Since radiators must often be attached to masonry walls or columns it is very desirable to reduce the number of bolts used for attaching them to a minimum. In the present invention the entire connection is made by 80 a single bolt or lag screw 33, inserted through an opening 34 in the upper end of the bracket 23. When the abutment 31 is formed on the end of a strap this may extend along behind the bracket and be secured to the wall 85 by the same bolt. The strap and bracket may be held against independent rotation by providing the latter with a lug 42 seating in a recess 43 in the former.

The leg 12 is provided with a foot 39 extending lengthwise alongside of the radiator and adapted to seat in the stirrup 13. The foot is much longer than the stirrup is wide, and has lugs 40 at its ends to limit relative movement of the foot in the stirrup. 90

In Figs. 4 and 5 the leg is shown as having a wedge-shaped block 35 adapted to be received between the columns 36 of a wall radiator. A block 37, also wedge-shaped, is received on the opposite side of the radi- 100

tor and the two are clamped in place by a bolt 38.

A radiator support made according to this invention permits one part, as the bracket 23, to be secured to a wall and the other part, as the leg 12, to be secured to a radiator, after which the radiator is mounted by simply lifting it to the desired height and hanging the foot 39 on the stirrup 13 and permitting the radiator to swing against the abutment 31. By making the foot 39 longer than the stirrup the bolts 33 need only be set in approximate position as to the distance between them, and by adjustably supporting the stirrup on the bracket these bolts need only be in approximate position as to height. This is a matter of considerable importance when the bolts are to be inserted in a masonry wall, on account of the great difficulty in drilling the wall at an exact point. Very frequently the selected point falls at the edge of a stone, brick, or other hard portion of the wall and the drill works off into the mortar or soft portion, causing the hole to be made at a greater or less distance from the selected point either laterally or vertically, or both.

By providing a structure that can be secured to the wall by a single bolt, the number of holes to be drilled are reduced to a minimum, and by locating that bolt at a point above the center of gravity of the radiator the drilling is done at such a height that the workman is not compelled to take an awkward or strained position. By making the foot 39 longer than the stirrup 13, the expansion and contraction of the radiator is readily accommodated by the support. At the same time the lugs 40 prevent any undue movement of the radiator with respect to the wall.

The straps 32 can be made very cheaply from scrap iron or bar stock. The stirrup and bracket can be readily made of cast iron, and the leg and clip or blocks can be readily made of malleable iron. In consequence the entire radiator support, in addition to being of simple construction, can be very economically produced.

While I have made use of specific description and illustration in order to fully disclose the invention, I do not intend to thereby limit the following claims or require a construction of them that will permit the substance of the invention to be appropriated without infringement.

I claim as my invention—

1. A radiator support comprising a leg, means carried by the upper end of the leg for securing the leg to a radiator at one side thereof and above the center of gravity and selectively along the height of the radiator, a foot on the leg, a stirrup receiving the foot, a bracket, complementary serrations on the stirrup and bracket, means for clamping the stirrup and bracket together, means for supporting the bracket and an abutment for en-

gagement with the radiator below the center of gravity thereof.

2. A radiator support comprising a leg, means for securing the leg at one side of the radiator above the center of gravity thereof, a foot on the leg, a relatively short upright bracket, a stirrup on the bracket receiving the foot, a relatively long strap behind the bracket and having an abutment below the center of gravity of the radiator and a bolt extending transversely through the strap and bracket and adapted to support them in operative position.

3. In a radiator support comprising the combination of a leg, means carried by the top of the leg for securing the leg to a radiator selectively along the height thereof, a foot carried by the leg at the side of the radiator, a stirrup to receive the foot, a slotted bracket having upright serrated surfaces, complementary serrated surfaces on said stirrup, and a bolt for clamping the stirrup and the bracket together.

4. A radiator support comprising a leg, a foot on the leg, means for securing the leg to a radiator above the center of gravity thereof, a stirrup for the foot, a relatively short upright bracket upon which the stirrup is adjustably mounted, a relatively long strap extending below the bracket and carrying an outwardly projecting abutment below the center of gravity of the radiator and a single bolt extending transversely through the bracket and strap above the stirrup and supporting them in operative position.

5. A radiator support comprising a leg, means carried by the leg at the top thereof for securing the leg to a radiator at one side thereof and selectively along the height of the radiator, a foot on the leg, a stirrup receiving the foot, a bracket, serrations on the bracket, a flange at each side of the serrations, complementary serrations on the stirrup engaging the serrations on the bracket, means for clamping the stirrup and bracket together and means for supporting the bracket.

6. A radiator support comprising a leg, means carried by the upper end of the leg for securing the leg to a radiator at one side thereof above the center of gravity and selectively along the height of the radiator, a foot on the leg, said leg being curved outwardly to space the foot from the radiator, a stirrup receiving the foot, a bracket adjustably supporting the stirrup, means for supporting the bracket and an abutment for engagement with the radiator below the center of gravity thereof.

7. A radiator support comprising a leg, means for securing the leg at one side of the radiator above the center of gravity thereof, a foot on the leg, a relatively short upright bracket, a stirrup on the bracket receiving the foot, a relatively long strap behind the

bracket and bent to form an abutment for the radiator below the center of gravity thereof, a bolt extending transversely through the bracket and a strap above the 5 stirrup and adapted to support them in operative position and means to prevent relative rotation of the strap and bracket on the bolt.

8. A radiator support comprising a leg, a 10 foot on the leg, means for securing the leg to a radiator with the foot at one side thereof and extending substantially parallel thereto, a supporting stirrup for the foot, said foot being relatively long as compared with the 15 stirrup and spaced lugs on the foot to limit sliding movement of the foot on the stirrup.

9. A radiator support comprising a leg and means carried by the upper end of the leg and including a yoke having notches adjacent its outer ends to engage successive radiator loops upon the inner side thereof, a clip opposed to the yoke having arms shaped to grip the opposite faces of the said successive loops, a bolt extending through the clip and 25 yoke, said bolt having a screw driver kerf therein and being adapted to cause the yoke and clip to firmly engage the said loops.

10. A radiator support embracing a wall bracket, a stirrup adjustable vertically upon 30 the bracket, a radiator leg to rest at its lower end in the stirrup and support a radiator thereon, a radiator engaging clamp carried by the upper end of the leg and capable of engagement with a radiator selectively along 35 the height thereof, and a wall abutment independent of the leg to engage the rear side of a radiator adjacent the bottom thereof.
